UNITED STATES PATENT OFFICE.

JAMES M. THOMPSON AND GEORGE P. FRENCH, OF STONEHAM, AND SETH D. TRIPP, OF LYNN, MASS., ASSIGNORS TO SAID SETH D. TRIPP.

IMPROVEMENT IN MACHINES FOR POLISHING THE HEELS OF BOOTS.

Specification forming part of Letters Patent No. 44,489, dated September 27, 1864.

To all whom it may concern:

Be it known that we, JAMES M. THOMPSON and GEORGE P. FRENCH, of Stoneham, in the county of Middlesex and State of Massachusetts, and SETH D. TRIPP, of Lynn, in the county of Essex and same State, have invented a new and useful Improvement in Machines for Polishing the Heels of Boots and Shoes; and we do hereby declare that the following is a full, clear, and exact description thereof, which will enable others skilled in the art to make and use the same, reference being had to the accompanying drawings, making part of this specification, in which—

Figure 1 represents our machine in plan. Fig. 2 is a side elevation of the same, the side of the polishing-wheel being turned to the beholder. Fig. 3 is a front elevation of the same.

Similar letters of reference indicate like parts.

A good degree of heat is required in bringing the blackball or wax with which the outside of the heel of boots and shoes is covered to the hardened and polished state which belongs to a good finish. Before machines were applied to this branch of the trade of shoemaking, it was always a laborious part of the making of a boot or shoe to blackball the heel, which was done by the aid of a steel tool heated at a fire or at the flame of a candle, which had to be lighted on purpose for this work. In order to lessen the expense and decrease the labor of the workmen in this part of the shoemaking process, we have invented a machine which will enable the workman or workwoman to do rapidly and with little exertion that which was formerly done with great exertion.

A standard, A, which carries the machine, is firmly secured to the flooring. At a suitable height in the standard to suit the position of the workman I place a shaft, S, which projects from opposite sides of the standard, so as to secure upon one end a driving-pulley, H, and

upon the other a polishing-wheel, B. A stud, D, is fixed in the standard, beneath the polishing-wheel, and from this a strap of leather or any equivalent material extends around the back part of the polishing-wheel and up to a tightening pin or screw, E, fixed in the standard, above the wheel B. By tightening the screw or pin E the strap C is strained against the wheel B and the friction produced heats the wheel when it is in motion.

Upon the front of the standard, on a line with the shaft S, is attached a right-angled piece of metal, F, in the position shown in the drawings, so that the projecting side thereof shall lie along the side of the wheel B and project beyond its periphery, as seen in Figs. 1 and 2. The object of this guard is to furnish a seat against which the bottom or sole of the heel may rest while the edge of the heel is pressed against the polishing-wheel. In a heel-polishing machine now in use the polishing-wheel has a flange upon it around its whole periphery. One objection to such a wheel is found in the fact that the blacking or wax gets upon the face of the flange and grinds it into the face of the heel, and another is that greater force is required to be used by the operator because of the greater bearing-surface of the wheel.

The wheel B may be of stone or metal, or any other suitable material.

We claim as new and desire to secure by Letters Patent—

1. Heating the polishing-wheel of heel-polishing machines by friction, substantially as described.

2. The independent guard-plate F, in combination with the polishing-wheel B, substantially as described.

JAMES M. THOMPSON.
GEO. P. FRENCH.
SETH D. TRIPP.
